UNITED STATES PATENT OFFICE.

GUSTAVO GALLOPIN, OF CHICAGO, ILLINOIS, ASSIGNOR TO WESTERN ELECTRIC COMPANY, INCORPORATED, OF NEW YORK, N. Y., A CORPORATION OF NEW YORK.

METHOD OF REPAIRING TORN FABRIC.

Application filed August 13, 1924. Serial No. 731,888.

This invention relates to a method of repairing torn fabric and, more particularly, to a method of repairing tracing cloth upon which drawings, such as factory working drawings, are commonly made.

The invention also contemplates a novel element employed in carrying out the method.

An object of the invention is to provide such a method whereby torn, mutilated or defaced material having a drawing thereon may be repaired and the injured part of the drawing reinstated without substantially impairing the translucency of the sheet so that it may satisfactorily be used for the purpose of obtaining prints therefrom.

Another object consists in obtaining the first named object in a very simple and expeditious manner.

A further object consists in providing a novel repair element for the purpose stated.

A further object consists in providing certain improvements in the material, construction and steps followed in carrying out the method, whereby the above named and other objects may effectively be attained.

A practical embodiment of the invention is represented in the accompanying drawings, in which—

Fig. 1 represents a detail, practically diagrammatic, view showing a portion of drawing fabric with a tear therein; an operation performed as a step in the method being represented in dot and dash lines.

Fig. 2 represents a plan view of an inset employed in carrying out the method.

Fig. 3 represents a view similar to Fig. 1 but showing the sheet repaired.

Fig. 4 represents an enlarged section taken in the plane of the line IV—IV of Fig. 3, looking in the direction of the arrows.

Fig. 5 represents an enlarged detail plan view of the repair element.

Fig. 6 represents an enlarged section taken in the plane of the line VI—VI of Fig. 5, looking in the direction of the arrows.

As is well known, mechanical working drawings in general are commonly made upon a form of brown paper and then traced onto oiled linen sheets which are used for a permanent record. From these linen sheets, blue prints are made from time to time for use by pattern makers, machinists, et cetera.

These permanent tracings are a very valuable part of factory equipment and it is im-

portant to keep them in good condition and fit for use in making accurate prints for the manufacturing operations.

It frequently happens that the said tracings become torn, mutilated or defaced, and such injury quite frequently takes the form of an actual tearing out of a portion of the tracing cloth. Such injury very frequently requires the retracing of the entire sheet onto a new sheet of tracing cloth so that facilities for producing prints may be maintained. This last step entails delay and substantial expense, and my invention is designed to obviate the same.

In carrying out my invention, a small piece of the same kind of tracing cloth is placed under the torn portion and a line cut around the torn portion so as to cut completely through the tracing cloth containing the drawing and the extra piece. The latter is then fitted in the opening in the tracing cloth drawing and secured in place by overlapping the same with a thin translucent fabric held in place by a translucent adhesive. The cut out portion of the drawing is then re-drawn on the inset, and the repair is complete.

Referring now to the drawings, the tracing cloth is denoted by 1. A conventional design drawn thereon is represented in two figures by 2 and 3.

The tear in the tracing cloth 1 is marked 4, and it will be noted that it has eliminated parts of the figure 2 of the design drawn thereon, in addition to mutilating the sheet 1.

With a tracing cloth drawing in this condition, the operator lays a similar piece of tracing cloth over the torn portion and cuts out the mutilated part of the sheet 1 by running a sharp edge around, following for example, the dot and dash line 5. This operation also cuts out a section from the extra piece that exactly fits the cut out portion of the tracing.

This makes an inset, which is represented in Fig. 2 and marked 6. This inset, it will be understood, is composed of the same material as the sheet 1 and it is now placed in the cut out portion in the sheet 1 so as to exactly fill out and complete the same, thereby restoring the mutilated sheet. I prefer to have one or more parts of the cut out portion 5 formed with a notched or crooked shape so as to assist in exactly matching the inset 6 with the sheet 1. This is represented

by the saw tooth line clearly shown in Figs. 1, 2 and 3.

With the inset 6 in place in the sheet 1, the operator makes an application of some translucent adhesive, such, for example, as colloidion, to the back of the insert 6 and to the surrounding portions of the back of the sheet 1.

He then applies a small patch of thin translucent fabric, such, for instance, as chiffon cloth, to the adhesive so that it covers the inset 6 and overlaps the cut out line 5 to include the immediately adjacent portions of the sheet 1. This patch is represented by dot and dash lines 7 in Fig. 3, and it is preferably cut in advance of its application to a convenient size for the purpose specified.

After application of the patch 7, it is pressed into firm adherence with the sheet 1 and inset 6 by suitable manual or mechanical pressure in any approved manner.

Finally, the operator re-draws, on the inset, the cut out portion of the drawing.

The mutilated sheet and its torn design have now been completely repaired and the sheet is fit for permanent record and for use in the production of prints therefrom, it being clear that the translucent nature of the patch 7 and adhesive will permit accurate and legible reproduction of the drawing on the prints.

Instead of securing the inset in place, before redrawing the cut out part of the drawing, the latter may be traced onto the inset before the cutting operation.

If desired, the patch 7 may have a coating of translucent glue applied thereto, after the manner of an ordinary postage stamp, 40 and it then may be fixed to the inset 6 and sheet 1 by moistening the glue and applying the patch in an obvious manner.

Such a form of patch is represented in Figs. 5 and 6, in which the fabric of the patch is represented by 8 and the glue coating thereon by 9. Such a patching material might be manufactured in ribbons or tape formation and dispensed in a roll or in any other suitable package, and in various 50 widths. It is plain that, from such a roll or package, a suitable amount of the desired width could be cut off and applied to the

inset 6 and sheet 1, as just explained. I believe this form of repair material for this purpose to be novel, and it constitutes a 55 feature of my invention.

It will be understood that various changes may be resorted to in the material, form, construction and steps followed without departing from the spirit and scope of my invention, and hence, I do not intend to be limited to the details herein shown and described, except as they may be included in the claims.

What I claim is:

1. A method of repairing mutilated drawing sheets of translucent material which includes the following steps: cutting out with a crooked cut a part of the sheet including the mutilated portion of the drawing, cutting out at the same time a piece of translucent material having an outline identical with that of the cut out portion of the drawing, inserting the piece of translucent material in place of such cut out portion of the drawing and securing said piece in position by applying to the back of said piece and said sheet a patch of translucent fabric with the intermediation of translucent adhesive, thereby leaving the front of the repaired sheet as a substantially smooth surface upon which may be redrawn cut out portions of the drawing.

2. A method of repairing mutilated drawing sheets of translucent material which includes the following steps: removing a portion of the sheet including the mutilated portion of the drawing, preparing a piece of translucent material having an outline identical with that of the removed portion of the drawing sheet, inserting the prepared piece of translucent material in place of such removed portion, and securing said piece in position by fixedly applying to the back of said piece and said sheet a patch of translucent material to produce a substantially uniformly translucent sheet having a substantially smooth front surface upon which may be redrawn cut out portions of the drawing.

In testimony, that I claim the foregoing as my invention, I have signed my name this 100 29th day of July, 1924.

GUSTAVO GALLOPIN.
